LENS FOR LIGHT FIXTURE

Kurt Franck and Vearl S. Wince, Newark, Ohio, assignors to Holophane Company, Inc., New York, N.Y., a corporation of Delaware

Application September 25, 1957, Serial No. 47,859

Term of patent 14 years

(Cl. D48—16)

Fig. 1 is a perspective view of a lens for light fixture showing the new design;

Fig. 2 is an enlarged section taken from outlined section 2 of Fig. 1;

Figure 3 is an enlarged section taken from outlined section 3 of Fig. 1;

Fig. 4 is an enlarged cross-sectional view taken on lines 4-4 of Fig. 1 with a portion omitted for convenience of illustration; and

Fig. 5 is an enlarged cross-sectional view taken on lines 5-5 of Fig. 1.

We claim:

The ornamental design for a lens for light fixture, as shown.
